UNITED STATES PATENT OFFICE

HOWARD JOHN FOUNTAIN, OF LONDON, ENGLAND, ASSIGNOR OF ONE-HALF TO THE
CLARKSON THIMBLE TUBE BOILER COMPANY LIMITED, OF LONDON, ENGLAND

WATER HEATER

Application filed June 6, 1930, Serial No. 459,504, and in Great Britain June 6, 1929.

This invention relates to water heaters or boilers and more particularly to water heaters or boilers of the thimble tube type or of the type having cross tubes and has for its object to provide an improved construction of such water heaters or boilers permitting the utilization of the heat of exhaust gases of combustion or of steam and of direct firing by oil or powdered fuel or gas, simultaneously or separately, but in such manner that no mixture of the separate combustion products takes place. The improved boiler is thus well adapted for use as a boiler where Diesel engines are used since the boiler can be direct fired when maximum steam out-put is required or a portion may be heated with exhaust gases and a portion by direct firing simultaneously, whilst keeping the products of combustion separate.

10 The improved boiler comprises the combination within a single outer shell or cylinder of a pair of inner thimble or tubed combustion chamber-forming cylinders placed end to end and closed at their inner ends which are separated by a water space, one of the chambers being adapted for direct oil, coal or gas firing and the other for indirect firing by exhaust gases or products of combustion. In the chamber heated by exhaust gases or products of combustion such exhaust gases or products of combustion may be supplied around the thimbles or tubes and withdrawn by way of a central tube. The flue outlet from the oil gas or coal direct fired chamber, may be connected with the flue inlet of the chamber heated by exhaust gases or products of combustion by a change over baffle or damper permitting in one position the discharge of the products of combustion to the atmosphere and in another position causing them to pass among the thimbles or tubes of the waste heat chamber and thence to the atmosphere.

15 The invention is illustrated in vertical section in Figure 1 of the accompanying drawings which shows a boiler of the vertical type having a combustion chamber direct fired by an oil burner and a combustion chamber heated by exhaust gases. Fig. 2 is a detail side elevation of a part of the apparatus.

Referring to the drawings, the improved boiler comprises in combination with a single vertically disposed outer shell or cylinder 1 bounding the water and steam space of the boiler a pair of combustion chamber-forming inner cylinders or shells 2 and 3 placed end to end and closed at their inner ends by covers 2', 3' which are separated as shown by a water space. These cylinders 2 and 3 are provided with tubes or as shown, with thimbles 4 extending radially inwards from the water space. The shell 2 is direct fired by an oil burner 5, there being fitted within said shell a cylindrical flue 6 of refractory material so arranged that the products of combustion from the burner 5 are carried upwards over the top of the flue 6 then downwards between the flue and the shell, 2, among the thimbles 4 before passing by way of a flue outlet 7 to atmosphere or to the other shell 3 through valve 17. The shell 3 in the example illustrated is heated by exhaust gases, being provided with a central tubular flue 8 depending from the inlet casing 9 for the exhaust gases. The flue 8 communicates with the atmosphere, the gases passing by way of the inlet 9 downwardly among the tubes 4 and then upwardly by way of the flue 8 to the atmosphere.

20 10 denotes the usual water baffle suitably supported within the water space of the boiler, 11 the usual inspection doors, 12 an anti-priming pipe located in the steam space, 13 the feed inlet and 14 the blow-down cock connection.

Draught can be introduced in the outlet flue 7 of the shell 2 in order to obtain sufficient draught to support combustion and at the same time give the necessary velocity to drive the gases through the waste heat shell 3. When the engine is not running and no exhaust gas is available at 9, a valve indicated at 16 is changed over to close pipe 9 and open communication with pipe 7 and an induced draught fan 15, inducing products of combustion from the oil-fired unit, causes them to pass through the upper unit and thence to the atmosphere.

25 It is to be understood that, although a vertical type boiler is shown, the invention is

applicable to boilers of the horizontal type.

I claim:

1. A water heater comprising the combination within a single outer steam and water drum of a pair of cylinders each forming a combustion chamber, said cylinders each formed with thimble tubes communicating with the water space of the drum and extending into the combustion chamber, said cylinders disposed end to end and closed at their adjacent ends, means for directly firing one of said combustion chambers, means for passing hot combustion products through the other of said chambers.
2. A water heater comprising the combination within a single outer steam and water drum of a pair of cylinders each forming a combustion chamber, said cylinders each formed with thimble tubes communicating with the water space of the drum and extending into the combustion chamber, said cylinders placed end to end and closed at their adjacent ends, a peripheral inlet for the supply of hot combustion products around the thimbles of one of said combustion chambers and a tubular baffle providing for the discharge of the combustion products spaced from said thimbles, and means for directly firing the other of said combustion chambers.
3. A water heater comprising the combination within a single outer steam and water drum of a pair of cylinders each forming a combustion chamber, said cylinders each formed with thimble tubes communicating with the water space of the drum and extending into the combustion chamber, said cylinders placed end to end and closed at their adjacent ends, a peripheral inlet for the supply of hot combustion products around the thimbles of one of said combustion chambers and a tubular baffle providing for the discharge of the combustion products spaced from said thimbles, a burner disposed centrally in the other of said combustion chambers, a refractory tubular wall between the burner and the thimbles of said combustion chamber and spaced from the latter and an outlet for the products of combustion communicating with the space between said thimbles and said refractory wall.
4. A water heater comprising the combination within a single outer water and steam drum of a pair of cylinders each forming a combustion chamber, said cylinders each formed with thimble tubes communicating with the water space of the drum and extending into the combustion chamber, said cylinders disposed end to end and closed at their adjacent ends, means for directly firing one of said combustion chambers, means for passing hot combustion products through the other of such chambers and a conduit connecting the outlet of one chamber with the inlet of the other chamber.
5. A water heater comprising the combination within a single outer steam and water drum of a pair of cylinders each forming a combustion chamber, said cylinders each formed with thimble tubes communicating with the water space of the drum and extending into the combustion chamber, said cylinders disposed end to end and closed at their adjacent ends, means for directly firing one of said combustion chambers, means for passing hot combustion products through the other of said combustion chambers and an induced draught fan for supporting combustion in the direct fired combustion chamber and imparting the velocity necessary to the gases to force them through the other combustion chamber.

In testimony whereof I have signed my name to this specification.

HOWARD JOHN FOUNTAIN.
